LIGHTING SYSTEM

William J. Eady, Anderson, Ind., assignor to General Motors Corporation, Detroit, Mich., a corporation of Delaware

Application March 25, 1938, Serial No. 197,980

2 Claims. (Cl. 177—311)

This invention relates to electric lighting circuits for automotive vehicles and particularly to the type of lighting circuit which provides for automobile parking, city driving, country driving and country passing.

It is an object of the present invention to provide a simple and effective device for indicating when a lamp filament has burned out. I aim to accomplish this object by the use of a single relay switch having two windings which are differentially related. When the differential in amperes exceeds a certain amount, the relay switch will close to energize a signal, preferably a visible signal, such as a lamp on the instrument board. I provide a main lighting circuit control switch which is so constructed and connected in the circuit that, regardless of whether the switch is set for city driving, country driving, or country passing, the ampere differential of the two relay windings is below the amperes required to close the relay; but if a single filament burns out, the differential will be above the operating ampere turns of the relay regardless of the position in which the main lighting switch is located for a driving condition.

Further objects and advantages of the present invention will be apparent from the following description, reference being had to the accompanying drawings wherein a preferred embodiment of the present invention is clearly shown.

In the drawings:

Figs. 1 to 4 inclusive, are similar wiring diagrams showing one form of embodiment of the present invention in four different conditions of operation.

Figs. 5 to 8 inclusive, are similar wiring diagrams of another form of the present invention showing the system in four different conditions of operation.

Fig. 9 is a fragmentary wiring diagram showing a modification of the diagram Fig. 5.

Fig. 10 is a simplified circuit diagram illustrating the features of the invention.

Referring to Fig. 1, H_r represents the right head lamp and H_l the left head lamp. Lamp H_r has filaments #2, #4 and #6 and lamp H_l has filaments #2, #5, and #8. The #2 filaments are for city parking, the #5 and #4 filaments are for country driving, and the #6 and #8 filaments are for city driving. The #6 filament is used also for country passing. Lamp #7 at the bottom of the diagram is the tail lamp. The source of current is the storage battery 20 which is grounded, as are all of the lamp filaments. The lighting current is distributed from the battery 55 through two main branches or circuits called, respectively, leg A and leg B. In the diagrams Figs. 1, 2, 3 and 4, the non-operative circuits are

indicated by the fine lines and the leg A circuit and its branch circuits are indicated in heavy black lines. The leg B circuit and its branches are indicated by the fine parallel lines.

5 It will be noted that leg A includes an electromagnet winding a of relay R and leg B includes an electromagnet winding b surrounding a magnetizable core c attached to the frame d which supports a hinged armature e spring urged into contact open position as shown. Armature e carries a contact f engageable with a contact g connected by wire h with an indicating lamp L grounded at m. The armature e is connected with the battery 20 either through the A circuit 10 or the B circuit.

The main switch S has stationary contacts 21, 22, 23, 24, 25, 26, 27, 28 and 29 and movable contacts which are in the form of triangular plates 30, 31 and 32. The movable contact plates 20 30, 31 and 32 are mechanically connected together, but not electrically, so that they can be operated by a push pull rod.

The parking position of switch S is shown in Fig. 1 in which it will be noted that contact 30 25 does not connect leg A with anything. Contact 31 connects leg A through contact 28 with contacts 27 and 22. Contact 32, though it connects contacts 24 and 28, does not complete any circuit. Only the head lamp filaments 2—2 and 30 the tail lamps 7 are burning, hence the legend,

"Park
A (2,7)"

appearing at the bottom of this figure.

35 Fig. 2 shows the city driving position of the switch. Leg A, that is, the heavy black line, is connected with head lamp filament 6 through contact 21, bridged by contact 30 with contact 26. Leg A is connected with tail lamp 7 through contact 23 bridged by contact 31 with contact 27. Leg B is connected with head lamp filament 8 by contact 32 which bridges contacts 28 and 29. For city driving, head lamp filament 6 and 8 and tail lamp filaments 7 are connected with the battery. Leg A delivers current to filaments 6 and 7 and leg B to filament 8. Hence, the following legend appears below the diagram Fig. 2:

"City driving
A (6,7)
B (8)"

Fig. 3 shows the switch S in condition for country driving. Leg A is connected with the tail lamp 7 and with head lamp filament 4 through contact 31 which bridges contacts 23, 24 and 27. The circuit to filament 4 is through a dimmer switch DS, which is not a resistance dimmer switch, but is a switch which shifts a con-

nection from a central contact either to the filament 4, which is the main driving filament for the right-hand head lamp, or to the filament 6 which is a depressed beam filament for the right-hand head lamp. The switch DS is conveniently mounted on the floor board of the vehicle and is operated by foot pressure operating through a mechanism involving a ratchet and pawl type of movement. Leg B is connected with head lamp filament 5 by contact 32 which bridges contacts 25 and 29. Therefore, for country driving, leg A supplies current to the tail lamp 7 and to the main filament 4 of lamp H₂ and leg B supplies current to the main filament 5 of lamp H₁. Hence, the following legend appears 15 below Fig. 3:

"Country driving
A (4,7)
B (5)"

Fig. 4 shows the condition of the lighting system for country passing. There has been no change in switch S; it is in the same position as for country driving, but the dimmer switch DS has been moved to transfer the connection in the 25 leg A circuit from filament 4 to the depressed beam filament 6. Hence there appears below this diagram the following legend:

"Country passing
A (6,7)
B (5)"

In order to aid in the understanding that this distribution of lighting current through the legs A and B for the various positions of the switches 35 which control the lighting circuits gives a differential below the operating differential of the relay when all of the selected filaments are burning and gives a differential between legs A and B which is above the operating differential of 40 the relay when one of the selected filaments burns out, the following five examples are given of a lighting circuit constructed and operated according to the diagrams Figs. 1 to 4.

EXAMPLE No. 1

Showing differential current in the coils of the relay at 8 volts, using 32 C. P. filaments #4 and #5 and 21 C. P. filaments #6 and #8 with all selected filaments forming:

City driving

It will be noted from the foregoing examples Nos. 1, 2 and 3, that the largest differential of current between the coils *a* and *b* of the relay with all the filaments burning is 1.31 amperes as in country passing. The smallest differential with one filament out is 2.17 amperes as in city driving. The relay should be set at 1.75 amperes to close the circuit of the tell-tale lamp *L* when one of the selected filaments goes out.

EXAMPLE No. 4

Showing differential current in the coils of the relay at 8 volts, which gives the maximum differential, using 32 C. P., filaments #4, #5, #6 and #8 with all selected filaments burning.

25 From examples Nos. 4 and 5 it is obvious that, with filament 8 or 5 defective, there will be a differential current between the relay windings of 5.84 amp. at 8 volts and 4.83 amp. at 5.5 volts. With filaments 6 or 4 defective, there will be a minimum differential of 3.77 amperes. The relay may, here, be set to close at 3 amperes.

In the preceding examples no consideration has been given to the parking circuit because the current flowing through leg A when parking is below the current required to operate the relay.

In the circuit shown in Figs. 5, 6, 7 and 8, there is a head lamp *H*₁ having a direct beam filament 4 and an auxiliary or depressed beam filament 6. The head lamp *H*₁ has a main or direct beam filament 5 and the auxiliary or depressed beam filament 10. Instead of providing the head lamps with parking filaments 2, as shown in Figs. 1 to 4, the system of Figs. 5 to 8 provides fender or marker lights 2. As in the Figs. 1 to 4, there is the tall lamp 7. The switch *S* has stationary contacts 41, 42, 43, 44, 45, 46, 47, 48, 49, 50 and 51 and movable contacts 52, 53 and 54. Contacts 48 and 49 are not connected together on the inside of the switch but there is a strap 55 on the back of the switch or terminal block which connects contacts 48 and 49. Contact 49 is connected with contact 45 on the back of the switch by a strap 56.

Fig. 5 shows the parking position of switch *S*. It will be apparent that leg A supplies current only to the marker lamps 2 and the tail lamp 7. Leg B supplies no current. Hence there appears below this diagram the legend,

60 "Park
A (2, 7)"

In the city driving position of the switch *S* contact 52 bridges contacts 41, 42 and 47. Contact 53 does not connect contact 43 with anything, although the lower point of contact 53 appears under the strap 55 which, as stated before, is not on the inside of the switch but is only on the outside. Thus leg A feeds current to marker lamps 2 and to filament 6 of head lamp *H*₁. Leg B is connected by contact 54 with contacts 50 and 45. Contact 45 is connected by strap 56 with contact 49 connected by strap 55 with lamp 7. Contact 50 is connected with filament 10. Hence leg B feeds current to tall lamp

1 and filament 10 of head lamp H₁. Therefore, below the diagram Fig. 6 appears the legend,

"City driving
A (6, 2)
B (7, 10)"

Fig. 7 shows the country driving position of switch S in which contact 52 makes no circuit connection with the battery. Contact 53 bridges contacts 43, 44 and 49. Contact 49 is connected by strap 55 with tail lamp 7. Contact 48 is connected with filament 4. Therefore, leg A supplies current to tail lamp 7 and to filament 4 of head lamp H₁. Switch contact 54 connects contacts 46 and 51. Hence leg B supplies current to filament 5 of head lamp H₁. Hence, there appears below the diagram Fig. 7 the legend,

"Country driving
A (4, 7)
B (5)"

Fig. 8 shows the country passing condition of the circuit. The switch S is not changed from its position shown in Fig. 7, but the dimmer switch DS is changed in order to divert current flowing in leg A from the filament 4 to the filament 6 and also to the marker lamps 2 through a connection established by the contact 52 which bridges contacts 47 and 42. Therefore, leg A supplies current to lamps 6, 2, and 7 and leg B supplies current to lamp 5. Hence, below the diagram Fig. 8 appears the legend,

"Country passing
A (6, 2, 7)
B (5)"

In order to understand how the system illustrated in Figs. 5, 6 and 7 effects distribution of current such that, in all driving positions of the main switch S, the differential in legs A and B is less than that required to operate the relay R when all the selected filaments are burning and is sufficient to operate the relay R in case one of the selected filaments burns out, Examples Nos. 6, 7 and 8 are given.

EXAMPLE No. 6

Showing differential current in the coils of the relay at 8 volts, using 32 C. P., filaments #4 and #5, and 21 C. P. filaments #6 and #10 with all selected filaments forming.

Diff. 4.20

From the foregoing examples Nos. 6, 7 and 8, it will be noted that the maximum differential between the coils with all of the lamps burning is .64 ampere as in country driving and that the minimum differential with one light out is 2.20 amperes as in city driving. Relay R should in this case be set to close at 1.75 amperes.

If the requirements of the system shown in Figs. 5, 6, 7 and 8 were for 32 C. P. filaments for all of the head lamp filaments #4, #5, #6 and #10, then the construction of the switch S could be much simplified. Fig. 9 shows the modification S' of switch S, which could be made if all of the head lamp filaments were 32 C. P. It will be noted that the contact 45 is omitted entirely and also the jumper 56. The contacts 48 and 49 are merged into one long contact instead of there being two contacts insulated from each other on the inside of the switch but connected on the back of the switch by a jumper strap 58. Otherwise the construction of the switch is the same. Therefore, when this switch is in parking position, as shown, leg A supplies current to lamps 2 and 1, and leg B is not energized. In the city driving position, leg A supplies current to filaments #2, #6 and #7, and leg B supplies current to filament #10. This is different from the city driving condition of the circuit according to Fig. 6. The country driving and country passing positions of the switch S' set up the same circuits as in Figs. 7 and 8, respectively, that is, when switch S' is in country driving position, leg A supplies current to filaments #4 and #7 and leg B to filament #5; and, when switch S' is in the country passing position, leg A supplies current to filaments #6, #2 and #7 and leg B supplies current to filament #5. In order to understand the operation of the lighting system shown in Figs. 5, 6, 7 and 8 with the switch S' substituted, the following Examples Nos. 9, 10 and 11 are given:

EXAMPLE No. 9

55

Showing differential current in the two coils of relay at 8 volts, which gives maximum differential, when using all 32 C. P. head lamp filaments with all selected filaments burning.

From the foregoing Examples Nos. 9, 10 and 11, it will be observed that the largest differential between the coils with all the lamps burning is 1.89 amperes as in No. 9, and that the lowest differential with any filament burned out is 2.77 amperes as found in city driving and country passing. The relay could be adjusted to close at 2.25 amperes, thus assuring its being open with all filaments burning and closed when any filament is defective.

With the system according to Figs. 5 to 8 but modified according to Fig. 9 and employing 32 C. P. main filaments #4 and #5, and 21 C. P. depressed beam filaments #6 and #10, it has been found that the relay will not give an indication in case the filament #6 burns out, with switch S' in the city driving position, because the differential between the coils is lower than that required to operate the relay under other conditions of operation of the circuit, such as, when the switch S' is either in the country driving position or in the country passing position. It is, therefore, necessary to use the switch S as shown in Figs. 5 to 8 when the requirements are that the depressed beam filaments #6 and #10 are 21 C. P. while the main filaments #4, and #5 are 32 C. P.

It will be noted that in the type of lighting circuit shown in Figs. 1 to 4, the possible current setting of the relay R is higher than with the system shown in the other figures, the current setting being as high as 3 amperes when 32 C. P. filaments are used in all of the driving filaments of the lamps. It will also be noted that the number of turns in the coil b in leg B could be increased with respect to the number of turns in the coil a of leg A. Then a somewhat larger differential in ampere turns can be obtained to take care of the worst condition of ampere differential between the condition with all the lights burning, and the condition with one light defective.

From the foregoing description of the construction and mode of operation of various lighting systems embodying the present invention, it is apparent that the invention contemplates the use of a main current distributing switch to which current from the battery is fed through two legs A and B, each leg including one of two differentially related magnet windings of a tell-tale relay magnet core. The main distributing switch is required to divide up the current flow between the legs A and B in such manner that, for all driving positions of the switch S, the differential in the legs A and B with all selected filaments burning is less than that required to operate the

relay R, but that when any one of the selected filaments burns out, the differential will be greater than that necessary to operate the relay R, whereby the relay R will be conditioned for operation 5 to connect the tell-tale signal lamp with the battery whenever the filament of a lamp burns out, the main switch being in a driving light position.

While the embodiment of the present invention as herein disclosed, constitutes a preferred form, 10 it is to be understood that other forms might be adopted, all coming within the scope of the claims which follow.

What is claimed is as follows:

1. A lighting system for automotive vehicles 15 comprising a current source, a plurality of filament circuits including head lamp main filaments, of a designated current draft, head lamp auxiliary filaments of a different current draft and a tail lamp filament, a signal lamp, a relay for connecting the signal lamp with the current source and provided with differential windings each connectible with separate filaments and which, if in approximate balance, maintains the signal lamp circuit open, and which, if out of balance by a certain amount, will close the signal lamp circuit, switching means for selectively connecting the current source with selected combinations of filaments and, for arranging the selected combinations in two circuits from the current 20 source, each circuit from the current source including a winding of the relay and a head lamp filament, said tail lamp filament, when the selected combination of head lamp filaments includes filaments of different current draft, being connected with the relay winding joining the filament of lesser current draft.

2. A lighting system for automotive vehicles comprising a current source, a plurality of filament circuits including head lamp main filaments of a designated candle power, and head lamp auxiliary filaments of a different candle power, each arranged in pairs, and a tail lamp filament, all connectible with the source in selected groups, a signal lamp for indicating the failure of a filament in a selected group, a relay 40 for connecting the signal lamp with the current source and provided with a pair of differential windings, switching means for selectively connecting like and unlike filaments of each head lamp, and the tail lamp filament as a group with the relay windings to the current source, and for arranging them in two branches, each of said branches including a winding of the relay, said tail lamp filament when unlike head lamp 45 filaments are selected, being connected with the relay winding in the branch including the head lamp filament of lesser candle power, the two branches from the switching means when connected with the current source requiring different amounts of current, and the respective relay windings, both branches connected with the current source effecting a differential of magnetism in the relay less than a predetermined value required to operate the relay in connecting 50 the signal lamp to the current source the arrangement of each relay winding with the selected filaments in series therewith being such that failure of one of the filaments so connected will increase the differential to such an extent as to exceed the predetermined value required to operate the relay, and thereby cause the relay to connect the signal lamp with the source.

WILLIAM J. RADY.
